CLAIM

(57) The ornamental design for an electric fryer, as shown and described.

DESCRIPTION

FIG. 1 is a perspective view of an embodiment of an electric fryer.

FIG. 2 is a right side elevational view of the electric fryer of FIG. 1.

FIG. 3 is a left side elevational view of the electric fryer of FIG. 1.

FIG. 4 is a front elevational view of the electric fryer of FIG. 1.

FIG. 5 is a back elevational view of the electric fryer of FIG. 1; and,

FIG. 6 is a top view of the electric fryer of FIG. 1. A view of the bottom has been omitted since the bottom is flat and devoid of surface ornamentation. The broken lines appearing in the figures are for the purpose of illustrating the environmental structure of the article of the claimed design and form no part of the claimed design.
